ATTORNEY

UNITED STATES PATENT OFFICE.

ALEXANDER STEWART, OF PHILADELPHIA, PENNSYLVANIA.

CUSPIDOR.

SPECIFICATION forming part of Letters Patent No. 276,496, dated April 24, 1883.

Application filed November 13, 1882. (No model.)

To all whom it may concern:

Be it known that I, ALEXANDER STEWART, a citizen of the United States, residing at Philadelphia, in the county of Philadelphia and State of Pennsylvania, have invented certain new and useful Improvements in Cuspidors; and I do hereby declare the following to be a full, clear, and exact description of the invention, reference being had to the accompanying drawings, which form part of this specification, in which—

Figure 1 is a side elevation of completed cuspidor. Fig. 2 is a transverse section of breast, or of bottom shell.

15 My invention has for its object to provide a sheet-metal cuspidor, which shall be stronger and more durable than any heretofore produced, and which will require but very little, if any, more material than that needed for cuspidors made in the ordinary manner.

20 My improvements consist, first, in making a sheet-metal cuspidor corrugated; and, second, in the special construction of a corrugated sheet-metal cuspidor, as hereinafter fully set forth.

25 Referring to the accompanying drawings, A represents a sheet-metal cuspidor comprising a throat, B, breast C, bottom shell, D, and foot E. The bottom shell is composed of the 30 bottom d and the wall or side d'. The throat and breast are made in separate pieces joined at b. The bottom shell, D, is also a separate piece, and is joined to the breast at c. The foot E may be used or not, as desired, being 35 constructed and, if used, attached in the usual or any suitable manner. The throat, breast, and bottom shell are corrugated, substantially as shown in the drawings, the corrugations being vertical, and preferably produced in the act 40 of forming the said parts by stamping or pressing flat plates of sheet metal, as described in Letters Patent of the United States granted to me, dated October 24, 1882, No. 266,548. The foot E may be also corrugated, similarly to the 45 throat, breast, and bottom shell. By preference the corrugations do not extend to the edges of the specified parts of the cuspidor,

said edges, or the metal adjacent thereto, being left plain, so as to produce smooth or plain joints where the parts meet at b c, and to permit the formation of a like plain or smooth wire edge or rim, b', for the throat. In some cases, however, I may corrugate the edges, or have the corrugations extend to the edges and make the joints and wired edge on the corrugations. The corrugation of the metal imparts great strength to the vessel, so that the material used in the manufacture of the same may be quite thin. The amount of metal thus required is very little, if any, more than that needed for cuspidors of the ordinary construction, while the corrugated cuspidors are vastly stronger and more durable than others.

55 In practical use ordinary sheet-metal cuspidors tend to break down or cave in in the throat and breast, owing to their being pressed into service as foot rests or supports; and they are also liable to have the bottom shell dented in the side by contact with the feet of persons meeting or moving them. By making these 60 parts corrugated, greatly increased powers of resistance are imparted to the vessels, rendering them stronger and more durable, without materially increasing their cost of production or weight.

75 What I claim as my invention is as follows:

1. As a new article of manufacture, a corrugated sheet-metal cuspidor, substantially as shown and described.

2. A cuspidor comprising a throat, breast, 80 and bottom shell, joined at b c, said parts being corrugated, substantially as shown and described.

3. The combination, in a cuspidor, of a throat, breast, and bottom shell, said parts being corrugated, and having plain or smooth edges, 85 substantially as and for the purposes set forth.

In testimony that I claim the foregoing I have hereunto set my hand this 8th day of November, 1882.

ALEX. STEWART.
